UNITED STATES PATENT OFFICE.

CLEO F. SCHURR, OF ST. GEORGE, KANSAS.

GATE.

1,078,003.

Specification of Letters Patent. Patented Nov. 11, 1913.

Application filed May 10, 1913, Serial No. 766,794.

To all whom it may concern:

Be it known that I, Cleo F. Schurr, a citizen of the United States, residing at St. George, in the county of Pottawatomie and State of Kansas, have invented a new and useful Gate; and I do hereby declare the following to be a full, clear, and exact description of the invention, such as will enable others skilled in the art to which it appertains to make and use the same.

This invention relates to a new and useful improved gate.

An object of the invention is the provision of an improved gate having novel means adapted to be actuated, by means remote from the gate on either side thereof, without the occupant of the vehicle getting out of his vehicle or rider dismounting, for automatically opening the gate.

In practical fields it may be found necessary to subject the various details of construction to alterations, to which the patentee is entitled, provided the alterations fall within the scope of what is claimed.

The invention comprises further features and combination of parts, as hereinafter set forth, shown in the drawings and claimed.

In the drawings:—Figure 1 is a perspective view showing the application of the improved gate. Fig. 2 is a side elevation showing the gate upon an enlarged scale partly broken away. Fig. 3 is a plan view of Fig. 2. Fig. 4 is a plan view of a portion of the gate showing the same opened on one side. Fig. 5 is a plan view of a portion of the gate showing the same opened to the opposite side. Fig. 6 is an edge view of the front end of the gate. Figs. 7 and 8 are detail views.

Referring more particularly to the drawings, 1 designates the hinge post, showing a portion of a wire fence 2 connected thereto while 3 denotes the latch post having another portion 4 of the wire fence connected to the same. Mounted upon the post 1 are hangers 5 and 6, while the latch keepers 7 and 8 are secured to the post 3, the construction of said keepers being clearly shown in the drawings.

The gate 9 is constructed of upper and lower end bars 10, 11, 12 and 13, which are constructed of tubular drawn metal. Hangers 14 and 15 are carried by the end bar 13, and are hung upon the hangers 5 and 6, as shown clearly in the drawing. Con-

necting the bars 10, 11, 12 and 13 are a series of vertically and transversely extending intersecting wires 16 and 17, including a diagonally extending brace rod 18, which constitutes means for reinforcing the structure 19 of the gate.

Secured to the upper portion of the bar or rod 13, by means of staples 19 and nuts 20 is a plate 21 having semi-circular recess 22 which receives the end bar or rod 13, the staples 19 arching about the bar or rod 13. Formed integrally with the plate 21 is a segment plate 23 having a segmental slot 24. This segment plate 23 is disposed horizontally, and whether the gate is closed, or opened in either direction, this segment plate always extends rearwardly and laterally.

Secured to the post 1 as at 25 and 26 is a bracket 27, which in side elevation is triangular in shape, and in plan view U-shaped in construction. Pivoted at 29 in the bracket 27 is a bell crank lever 30 having a short arm 31, and rather an extremely long arm 32. The short arm 31 at one end terminates in a bifurcation 33 extending upwardly, and between the arms of the bifurcation 33 a coupling plate 34 is pivoted upon the pin 35. The coupling plate 34 is provided with an aperture in which the downwardly extending lug or projection or lug 37 is arranged. This projection or lug 37 forms an integral part of the link or rod 38, the end portion 39 of which terminates in a downwardly extending lug or projection 40, which passes through the segmental slot 24, there being washers 41 above and below the segment plate 23. Cotter pins 42 are provided for holding the washers 41 in place, while cotter pins 43 are provided for holding the washers 44 in place upon the projection or lug 37. The lower end of the arm 32 terminates in an eye 45, to which cables, cords or the like 46 and 47 are connected. The cables 46 and 47 pass over pulleys 48 and 49, carried by the upper end of the post or standard 50.

Posts 51 and 52 are provided, one upon each side of the gate. These posts 51 and 52 are braced relative to the standard or post 50 by the guy wires 53 and 54, which are provided with hangers 55. The cables, ropes, cords or the like 46 and 47 pass through and are guided by the hangers 55, so as to prevent sagging of the same. The cables or ropes 46 and 47 pass over pulleys 56.

56 carried by the posts 51 and 52, and one end of each cable or rope 46 and 47 terminates in handles 57 and 58.

The long arm 32 of the bell crank lever 30 is provided with a series of apertures 59, in any one of which the pin 60 of the weight 61 may be inserted, for holding the weight 61 in adjusted positions upon the arm 32. For instance, if the weight 61 is arranged 10 adjacent the extreme end of the arm 32, the arm 32 will lower more quickly than if the weight is adjusted closer to the pivot 29 of the lever 30.

When one or the other of the cables 46 and 15 47 is pulled, by taking hold of the handle 57 or 58, the arm 32 of the lever 30 will be raised, while the short arm 31 will move toward the gate, thereby causing the lug or projection 40 of the link or rod 39 to move 20 in the segmental slot 24, until the lug 40 reaches the end 63 of the slot 24, that is, when the gate is in a closed position, and then when the bell crank lever 30 returns to its normal position owing to the gravitation 25 of the weight 61, the lug 40 will engage the shoulder 64 of the segmental slot 24, thereby moving or rocking the segment plate 23 and with it the gate, throwing the same open as shown in Fig. 3. After the 30 driver or rider has passed through the gate, the cable upon the opposite side thereof may be pulled, in order to close the gate. In this case the lug 40 moves in the slot 24 until it reaches the end 66, and then as the 35 long arm 32 returns to its normal position, the lug or projection 40 engages the shoulder 67, thereby rocking or moving the segment plate 23 back to its normal position, which closes the gate. In order to throw 40 the gate open upon the side opposite to that above described, it is necessary to loosen the nuts 20 of the staples 19, and adjust the segment plate just the opposite to that shown in Fig. 3, in which case the gate may be 45 opened toward the opposite side to that above described.

Secured to the lower bar 11 of the gate adjacent its free end is a bracket 68, and connecting the upper bar or rod 10 and the 50 end bar or rod 12 are L-shaped brackets 69. Pivoted in the brackets 68 and 69 are the lower and upper latch members 70 and 71, which are connected by the bar 72. The upper latch member is provided with an up- 55 wardly extending short arm 73 extending at right angles to the latch member. Connected to the short arm 73 is a wire or cable 74 passing over a pulley 75, with its rear end connected in an eye 76 of the long arms 60 32 of the bell crank lever 30. It will be seen that as the bell crank lever is tilted upon its pivot, the latch members 70 and 71 will be automatically raised out of engagement with their keepers 7 and 8 of the post 65 3. The latch members 70 and 71 are guided,

when raised and lowered by the straps 78 and 79. When the latch members 70 and 71 are raised, the spring 80 is put under tension. However, to hold the latch members in their raised positions, a latch member supporting device 81 pivoted at 82 to the bar or rod 12 is automatically thrown or swung upon its pivot by the spring 83, so that the shoulder 84 will assume a position in the path of the upper latch member 71, 75 so as to prevent its return to its normal position after once having been raised, and as the bar 72 is connected to the latch member 70, the said latch member 70 is likewise prevented from returning to its normal position. After the latch members have been raised, which is accomplished upon the upward movement of the long arm 32 of the lever 30, the gate is free to be opened, and which is accomplished by the 80 lug or projection 40 engaging the shoulder 64, as the long arm 32 of the lever 30 turns to its normal position by the gravitation of the weight 61. When the gate is thrown closed, the lower end of the latch supporting device contacts with a lug 86, which tilts the device 81 upon its pivot withdrawing the shoulder 84 from the path of the upper latch member 71, and through the action of the spring 80, the latch members 85 will again engage their keepers 7 and 8. The lower end of the spring 83 may be connected to any one of the eyes or hooks 88, whereby the action of the spring may be 90 increased or decreased.

From the foregoing it is apparent that there has been devised an efficient and simple gate operating mechanism, which may be operated from either side of the gate for opening the same, and one which has been 105 found desirable and practical.

The invention having been set forth, what is claimed as new and useful is:—

1. In combination with a swinging gate provided at its hinged end with a segment plate provided with a segmental slot including a shoulder at each end, and a mechanism including a device working idly in said slot upon the initial actuation of said mechanism, said mechanism including a gravity actuating member to cause said device to engage one or the other of said shoulders to open the gate, and a latch mechanism on the gate having connections with said mechanism and adapted to be actuated upon the 115 initial actuation of said mechanism.

2. In combination with a swinging gate provided at its hinged end with a segment plate provided with a segmental slot including a shoulder at each end, and a mechanism including a device working idly in said slot upon the initial actuation of said mechanism, said mechanism including a gravity actuating member to cause said device to engage one or the other of said shoulders 125 130

to open the gate, and a latch mechanism on the gate having connections with said mechanism and adapted to be actuated upon the initial actuation of said mechanism, and means for holding the latch mechanism actuated while the gate is open.

3. In combination with a swinging gate provided at its hinged end with a segment plate provided with a segmental slot including a shoulder at each end, and a mechanism including a device working idly in said slot upon the initial actuation of said mechanism, said mechanism including a gravity actuating member to cause said device to engage one or the other of said shoulders to open the gate, and a latch mechanism on the gate having connections with said mechanism and adapted to be actuated upon the initial actuation of said mechanism, and means for holding the latch mechanism actuated while the gate is open, and an element upon the latch post to trip said last named means to release the latch mechanism as the gate reaches the closed position.

4. In combination with a swinging gate provided at its hinged end with a segment plate provided with a segmental slot including a shoulder at each end, and a mechanism including a device working idly in said slot upon the initial actuation of said mecha-

nism, said mechanism including a gravity actuating member to cause said device to engage one or the other of said shoulders to open the gate, and means whereby said gravity actuating member can be adjusted to increase or decrease the swinging action of the gate upon opening the same.

5. In combination with a swinging gate provided at its hinged end with a segment plate provided with a segmental slot including a shoulder at each end, and a mechanism including a device working idly in said slot upon the initial actuation of said mechanism, said mechanism including a gravity actuating member to cause said device to engage one or the other of said shoulders to open the gate, and means whereby said gravity actuating member can be adjusted to increase or decrease the swinging action of the gate upon opening the same, and a latch mechanism on the gate having connections with said mechanism and adapted to be actuated by the initial actuation of said first mechanism.

In testimony whereof I have signed my name to this specification in the presence of two subscribing witnesses.
